UNITED STATES PATENT OFFICE.

ALFRED SODERLING, OF CHICAGO, ILLINOIS.

COMBINED CHAIR AND SHOE-POLISHING CABINET.

No. 911,082.

Specification of Letters Patent.

Patented Feb. 2, 1909.

Application filed June 19, 1908. Serial No. 439,274.

To all whom it may concern:

Be it known that I, ALFRED SODERLING, citizen of the United States, and resident of Chicago, in the county of Cook and State of Illinois, have invented certain new and useful Improvements in a Combined Chair and Shoe-Polishing Cabinet, of which the following is a full, clear, and exact specification.

This invention relates to improvements in combined shoe polishing cabinets and chairs, in which the cabinet is secured from view within the chair and rendered accessible by the hinged chair seat.

The prime object of the invention is not only to provide a suitable receptacle for the polishing compound, the brush, etc., for applying it, but more especially for the polishing fabric-strip, the use of which is necessitated by the modern use of polish or paste.

A further object of the invention is to have the polishing fabric strip so located and fixed within the chair that by the user placing his foot on the edge of the chair the polisher may be conveniently reciprocated back and forth across the shoe from the roller by the employment of but one hand.

Another object of my invention is to have the polish-strip so mounted and secured within the chair that it may be automatically coiled about the roller in compact form, when not in use, while at the same time the roller operates it in one direction when the strip is in use.

Another object is to have the polishing strip mounted upon a spring roller supported and concealed within the chair seat, and in such a manner that the roller may be bodily swung upon a vertical axis in order to give the varied and necessary direction to the plane of the reciprocation of the polishing strip.

With these ends in view, my invention consists in certain features of novelty in the construction, combination and arrangement of parts, by which the said objects and certain other objects hereinafter appearing are attained, all as fully described with reference to the accompanying drawings, and more particularly pointed out in the claims.

Similar characters of reference indicate the same parts in the several figures of the drawings.

In said drawings, Figure 1 indicates a

vertical section through a combined chair and shoe polishing cabinet on the line 1—1 of Fig. 2, and showing the polishing roller in cross section with its vertical pivot in side elevation, and Fig. 2 is a horizontal section on the line 2—2 of Fig. 1.

60

In the said drawings 3 indicates an ordinary, and preferably, a kitchen or hall chair, the seat frame 4 of which is supported upon four legs, 5, 5, connected by the usual front and back bars, 6, 6, and side bars 7, 7, and is provided with the usual front and back rungs, 8, 8, and side rungs, 9, and may be provided with the usual back 10. The said frame has its rear end in two parts secured together by a hinge 11, so that it may be elevated to the position shown in dotted lines in Fig. 1, and when so elevated inclined sufficiently to rest against the back 10. Fitting within said frame is a box 12, which is, as shown, of octagonal shape, but which may be of any other form, secured in place by screws 13, passing therethrough into the bars 6.

The cabinet is entirely inclosed and concealed by the seat frame within which it fits and by the seat, the edge of the frame forming a foot rest for the user when the seat is elevated.

Supported upon the bottom of the cabinet is a bar 14, having at opposite ends brackets 15, 15, rising at an angle thereto and forming bearings for a roller 16, the member 14 being swiveled to the bottom of the cabinet by means of a bolt 17, passing through the center of the bar and through the bottom of the cabinet upon the underside of which latter is a nut for locking the bolt against accidental detachment. In other words, the roller is swiveled so that it may freely turn on a vertical axis to differing angles and thereby provide for the polishing strip being so directed as to polish the shoe on its several sides.

The roller 16 is a spring actuated roller, as for example, like an ordinary spring actuated shade-roller, and has secured thereto at one end a fabric strip 19 wound thereon and provided at its free end with a hand-hold 20, also serving as a stop, preventing the roller from entirely unwinding its spring, when the polishing strip, is released from the grasp of the user, and to which end the hand-hold is of sufficient thickness to prevent the end

passing beneath and between the roller, and the roller support 17.

When it is desired to operate the polishing strip, the seat is raised to the position shown 5 in dotted lines in fig. 1, the operator, after taking hold of the hand-hold 20 and partly unwinding the polishing strip then rests his foot on the edge of the chair, pulls the polishing strip down upon and across his shoe in 10 one direction, and when the polishing strip has reached the limit of its unwinding, the user then stops pulling, and permits the spring to actuate the strip, the result being that the strip operates upon the sides of the 15 shoe in both directions. Owing to the swiveling of the roller, the strip may be reciprocated in different directions, and still be retained in a wound condition, the result being that it may be pulled out at differing angles, 20 and that a perfect polishing of the shoe by the same manipulation of the strip, as if it were held by a second person, as it is usually done when polishing shoes with fabric strips.

The essential feature of my invention in 25 addition to having a polishing strip concealed within a chair offering a convenient footrest for the operation of the strip is in having a strip automatically actuated in one direction and capable of being shifted at differing angles 30 without wrinkling or buckling and therefore my invention is not limited to the particular form and arrangements of the pivotal support for the roller, for obviously this may be mechanically varied in form and arrangement 35 and the results above referred to be secured.

Having now described my invention, what

I claim and desire to secure by Letters Patent is:

1. A combined chair and shoe polishing 40 cabinet comprising in combination, a chair body, a hinged seat therefor, a cabinet secured within the seat frame, a roller therefor supported within the cabinet, a polishing strip secured to said roller, and means for actuating the roller to wind the strip thereon, substantially as described.

2. A combined chair and shoe polishing cabinet comprising in combination a chair, a seat hinged at one side thereof, a cabinet secured to the chair adjacently below the seat, a roller and a support therefor pivoted in the cabinet, a strip secured to said roller and means for actuating the roller to wind the strip thereon, substantially as described. 50

3. A combined chair and shoe polishing cabinet comprising in combination a chair, a seat supporting frame, a cabinet confined with said frame, a seat hinged to one side thereof, a roller, a polishing strip secured 60 thereto, a spring for automatically actuating the roller to wind the strip thereon, a frame supporting the said roller and a swivel for said support whereby the roller may be moved about an axis at a right angle thereto, substantially as described. 65

In witness whereof, I have hereunto set my hand and affixed my seal, this 11th day of June A. D. 1908.

ALFRED SODERLING. [L. S.]
